[57] CLAIM

The ornamental design for a record album jacket opener, as shown.

DESCRIPTION

FIG. 1 is a perspective view on a reduced scale looking downward toward the obverse face of a record album jacket opener showing my new design.

FIG. 2 is an elevational view of the same taken from the left end of FIG. 1.

FIG. 3 is an elevational view as seen from the right end of FIG. 1.

FIG. 4 is an elevational view of the reverse face of the structure of FIG. 1.

FIG. 5 is a top plan view thereof.

FIG. 6 is a bottom plan view thereof.
